SCOURING DEVICE

Filed May 7, 1929

INVENTOR.

Daniel J. Mayer,
BY
George D. Richards
ATTORNEY

UNITED STATES PATENT OFFICE

DANIEL J. MAYER, OF BELLEVILLE, NEW JERSEY, ASSIGNOR TO METAL TEXTILE CORPORATION, OF ORANGE, NEW JERSEY, A CORPORATION OF DELAWARE

SCOURING DEVICE

Application filed May 7, 1929. Serial No. 361,083.

This invention relates to improvements in scouring devices, and, more particularly, to scouring devices of the dish and bottle mop type; this application being a continuation in part of the subject matter disclosed in my co-pending application for United States Letters Patent, Serial No. 268,859, filed April 10, 1928, and which has resulted in Patent No. 1,713,975, granted May 21, 1929.

10 The present invention has for its principal object to provide in combination with a handle stick a mop head comprising an abrasive mass made of metallic wire or a composite of metallic wire and textile yarn so 15 doubled on itself as to provide a multiplicity of loop ends radiating from a common center, and bound together by a restrictive holding means which is provided with a shank portion adapted for insertion in the end of the 20 handle stick in fixed connection therewith.

The invention has for a further object to provide a novel combination of mop head and handle stick wherein the former fully encloses the end of the latter, so that the mop 25 head may be laterally pressed against the sides of bottles, dishes, etc. in a manner whereby the abrasive material is backed by the stick and easily pressed with effective scouring action sidewise as well as endwise; and 30 to this end the radial loops of the lower half of mop head are adapted to dispose themselves in downward overlapping relation to and around the end portion of the handle stick; and, furthermore, the sides of the 35 handle stick below the extremity to which the mop head is secured, is annularly undercut to form a retaining seat into which the overlying mass of the mop-head loops may be seated when lateral pressure is exerted to press 40 the side of the mop head against a surface to be scoured; said retaining seat serving to hold the engaged mop head material against displacement under reciprocable movement 45 of the mop head against the surface to be scoured. It will thus be obvious that the mop head may be effectively manipulated against both the bottom and sides of receptacles such e. g. as bottles, jars, bowls, etc. 50 with full assurance that a portion of the mass

of the mop head is always available for service under either condition.

Other objects of this invention, not at this time more particularly enumerated, will be clearly understood from the following description of the same.

An illustrative embodiment of the invention is shown in the accompanying drawings, in which:—

Fig. 1 is a side elevation of the novel dish and bottle mop made according to and embodying the principles of this invention; Fig. 2 is a fragmentary, more or less schematic, vertical longitudinal section of the same; and Fig. 3 is a detail view showing the manner in which the loops of material from which the mop head is formed are arranged so as to provide a compact central heart from which the said loops may radiate.

Similar characters of reference are employed in the above described views, to indicate corresponding parts.

The mop head is, in its essential characteristics, formed of metallic material preferably in the form of flat ribbon-like wire or wire of angular cross sectional shape *a*, which is turned or twisted upon itself to provide a roughly spirally convolved strand, thus furnishing a multiplicity of lateral scraping edges or projections. Preferably the metallic material is thus convolved or twisted about a central carrier strand of textile yarn *b*, whereby the former is retained against undue stretching or deformation of desired scraping edge forming convolutions or projections. The abrasive material thus provided is looped back and forth upon itself with the intermediate portions of gathered or bunched together into a compact central portion restrictively engaged and retained by a binding member, so that a multiplicity of loop ends *c* radiate from the central portion in all directions. The binding member consists in a binding wire arranged to form an encircling element *d* about the central portion, but with the ends of such encircling element *d* twisted together so as to form a shank portion *e* extending outwardly therefrom. In order to assure a firmly compacted central 100

portion, whereby the loop ends *c* are caused to more uniformly radiate in all directions, I find it preferably to draw out or stretch the convolved metallic wire on the carrier strand *b* at the center portions of doubled back strands whereby the loops are formed, thereby attenuating the metallic material to cause the same to closely hug said center portions so that when the attenuated portions 10 thus provided are brought together within the embrace of the encircling binding element *d* a very tight and well consolidated central heart is provided. The attenuated sections of the metallic material adapted to form this 15 consolidated central heart are indicated by the reference character *f*.

It will be understood that any kind of metallic material may be used in the making of the mop head as above described; it is preferable, however, to employ a non-rusting or non-corrosive metal. I have found copper a very satisfactory metal for the purpose.

The reference character *g* indicates a handle stick to which the mop head is attached. 25 This handle stick is provided at one end with a concave seat *h*, and extending axially into the handle stick body from the bottom of the seat *h* is a bore or opening *i*. To assemble the mop-head with the handle stick *g*, the 30 shank portion *e* of the binding member is inserted and driven into the bore or opening *i*. If desired, a suitable cement or glue may be employed to coat the inserted shank so as to adhesively fix the same to the handle stick 35 body. The shank portion *e* is driven into the handle stick until the consolidated heart of the mop-head and its encircling element *d* are drawn firmly down into the concave seat *h*. The adjacent loop ends *c* are separated so as 40 to allow the end of the handle stick to extend into the central heart, whereupon said adjacent loop-ends *c* will overlap the end portion of the handle stick so as to surround the same, as indicated more especially in Fig. 2. 45 The exterior surface of the handle stick end portion underlying the surrounding loop ends *c* is preferably annularly undercut to thus form an annular seat *j* beneath the margins *k* of the extremity of the handle stick. 50 As will be understood from an inspection of Fig. 2 of the drawings, the surrounding loop ends *c* will, when the mop-head is pressed laterally against a surface to be scoured, be forced yieldingly back into said seat *j*, and 55 consequently the loop end material will be braced or held against displacement when the mop-head is reciprocated under such laterally applied pressure, and consequently the loop end material may be effectively moved 60 against the surface to be scoured without loss of the desired abrasive effect by reason of displacement of the loop end material.

From the above description it will be apparent that this invention provides a dish and bottle mop having an abrasive head so re-

lated to a handle stick as to completely envelop the end portion of the latter, and consequently the mop may be variously manipulated under either endwise or sidewise pressure with full assurance that the material of the mop head is brought into operative scouring relation to surfaces to be cleaned in either case.

Having thus described my invention, I claim:—

A dish mop, comprising a metallic gimped carrying strand looped upon itself with the center portions of said strand intermediate the free loop ends thereof bunched together to form a consolidated central heart from which the free loop ends radiate in all directions, a binding element encircling and holding said central heart, said binding element having an outwardly extending shank, a handle stick having an end axially bored into which said shank is inserted and secured to attach said mop head to the handle stick with adjacent free loop ends of the former overlapping and surrounding the free end portion of the latter, said end-portion of said handle stick underlying said surrounding free loop ends having an annularly undercut seat in which the latter may engage when laterally pressed and reciprocated against a surface to be cleansed.

In testimony, that I claim the invention set forth above I have hereunto set my hand this 3rd day of May, 1929.

DANIEL J. MAYER.
